SODIUM LAMP

John W. Marden, East Orange, and George Meister, Newark, N. J., assignors to Westinghouse Lamp Company, a corporation of Pennsylvania

Application June 22, 1934, Serial No. 731,804

9 Claims. (Cl. 176—122)

This invention relates to electric discharge tubes and relates more particularly to a discharge chamber surrounded by a sealed envelope to provide the discharge with a heat insulating enclosure.

In co-pending application Serial No. 668,506 filed April 29, 1933 and assigned to the present assignee, a discharge lamp is shown and described in which a plurality of cold electrodes are employed in conjunction with a hot electrode or cathode. The construction shown and described is directed primarily to a sodium lamp operable on alternating current.

It is well known that, when operating a lamp such as that shown in the above identified pending application or other lamps in which a metal solid at room temperatures is employed, it is necessary to provide a structure in which means are employed for maintaining the necessary temperature conditions to keep the sodium or other metal at a temperature necessary to maintain the vapor condition.

Heretofore in devices of such character that it was necessary to conserve the heat from the discharge, it was the practice to enclose the discharge device in what was termed a vacuum bottle construction. This vacuum bottle form of enclosure was relatively expensive and required a double wall of glass and necessarily increased the size of the device and made it difficult to construct a lamp with a base in accordance with the common lamp practice.

The relatively large dimensions of the enclosure together with the difficulty in uniting or supporting such an enclosure in proper relation to the discharge device, caused certain practical difficulties and it was not only a disadvantage from an economical and appearance standpoint, but made it necessary to increase the size of the base and to provide means for supporting the vacuum bottle enclosure in a base and to support the discharge device in proper relation to the enclosure.

In lamps employing a metallic vapor such as sodium it is difficult to confine the vapor when condensed to portions of the device not in the effective path of the light rays.

It is desirable to keep the condensed sodium in position to be quickly heated and vaporized. If the sodium becomes condensed in the ends of the bulb a considerable time is necessary to heat it for vaporization to obtain a good light. In accordance with the present invention means are employed for providing a relatively cool area on the bulb at one side adjacent to the electrodes so that any sodium that may condense during

the operation of the lamp will become deposited on the cooled surface. This surface may be so positioned as to be in the rear of the lamp or adjacent to a reflector as when the lamp is mounted in a lighting housing. When the lamp cools off, the provided area being at the lowest temperature the sodium will condense thereon and be disposed in the most advantageous position for heating when the current is again turned on.

The above is accomplished by providing metallic contacts on the surface of the bulb so that heat is conducted away and the surface cooled. The same object may be attained by providing the bulb with a radiating fin formed of the glass but it has been found that a metallic strip or a plurality of metallic contacts give good results and are more practical from a manufacturing standpoint.

Although the above outlined feature is of particular advantage in connection with metallic vapor discharge devices generally, it is especially effective with a device constructed in accordance with the present device in which the discharge chamber is provided with a single enclosing envelope.

It is an object of the present invention to provide a lamp having a discharge chamber and an integral enclosing vacuum chamber.

Another object of the invention is to provide a discharge device consisting of a discharge chamber having an enclosing vacuum in an enclosing compartment sealed to said chamber.

Another object of the invention is to provide a discharge device comprising a chamber having means for supporting electrodes and an outer integral sealed envelope.

Another object of the invention is to provide a device of the character described in which the condensed vapor is confined to a predetermined area.

Another object of the invention is to provide a metallic vapor discharge device with means for causing condensed vapor to deposit on such portion of the bulb as to be subjected to heat to facilitate starting of the device.

Other objects and advantages of the invention will be more fully understood by reference to the accompanying drawings in which

Fig. 1 is a side elevational view of a device constructed in accordance with the present invention showing a double-walled envelope in section with electrodes supported therein;

Fig. 2 is a view taken on line II—II in Fig. 1; Fig. 3 shows a complete bulb constructed in ac-

cordance with the present invention and having a base applied thereto;

Fig. 4 is a modified form of the construction shown in Fig. 1 and discloses an inner discharge chamber supported by means of support members extending from a portion of the outer chamber;

Fig. 5 is a view taken on line V—V in Fig. 4;

Fig. 6 is a modified tubular form of the device in which an inner tubular chamber is supported concentric with an outer tubular envelope;

Fig. 7 is a view taken on line VII—VII in Fig. 6 and

Fig. 8 is a modification of a support member shown in Fig. 4.

15 A lamp constructed in accordance with the present invention may comprise an outer sealed envelope 10, and an inner discharge chamber 11. The discharge chamber may contain electrodes 12—13 and 14—15 and a cathode 16 as shown in Figs. 1 and 3. This construction is similar to that shown in the above mentioned copending application and will be more fully described herein-after.

As shown, the sealed envelope may be of tubular form and have a reentrant tube or stem 17. The chamber 11 may also be of tubular form disposed concentrically within the envelope 10 and may be provided with a neck portion 18 fitting the reentrant tube 17. A clamp collar 19 may be employed to grip the end of the neck and a packing ring 21 of suitable material as resilient material to hold the chamber 11 against endwise movement. Conductive support wires or members 22—23 for the electrodes and similar wires 35 24—25 for the cathode may be sealed through a press 26 closing the reentrant tube 17.

30 The usual flexible conductors 20 may be connected to the support members for the supply of electrical energy from a suitable source (not shown). An exhaust tube 27 is provided for exhausting the device or the exhausting operation may be performed through a tubulature at one end of the bulb and tipped off.

The chamber 11 is provided with a quantity of 35 sodium or other vaporizable material or ionizable medium together with a gas for promoting initial ionization and the neck of this chamber is closed by a partition 28 cemented in place. This closure may be a disk of mica and serves to seal the chamber against the escape of the ionizable medium but need not be a seal of the character employed for the outer bulb 10 since the operation of exhausting the outer bulb may serve to exhaust the inner chamber. The inner chamber may, however, be exhausted and supplied with the metal vaporizable material before it is mounted in the outer bulb. When constructing a device such as shown in Figs. 1 to 3, the inner chamber is completed with its internal electrode structure and is 40 mounted on the tube 17 which is provided with a flange 29. This flanged tube and chamber 11 is then inserted into the bulb 10 and sealed at 31 to the neck portion 32 thereof. The bulb 10 may then be exhausted by means of the exhaust tube 27 and a suitable base 33 secured to the neck of the device in the usual manner, and a rare gas, as for example, neon, may be admitted. The neon serves, in the chamber 11, to cause the initial ionization as found desirable with devices of the 45 present character. The neon gas enters the chamber 11 as well as the chamber 10 but it has been found that a metallic vaporizable material such as sodium does not escape into the outer envelope.

75 In the device shown in Figs. 1 to 3 electrical

energy may be supplied and the cathode 16 is heated, the medium becomes vaporized and ionized resulting in a glow discharge. The initial ionization occurs between two starting tips 34 and 34'. The structure shown is operable on alternating current and a discharge occurs between electrodes 13 and 14 and cathode 16 during one-half cycle and electrodes 12—15 and the cathode 16 during the other half of the cycle. With this construction it is possible to operate with a current of relatively low density. With a current of say five amperes supplied, the two electrodes will receive the current and divide it and by reason of the relatively large surface area of the electrodes the current density is reduced per unit 15 area.

The device shown in Fig. 4 employs two electrodes 35 and 36 and a cathode 37 enclosed in a chamber 38 of tubular form disposed concentrically of a tubular sealed bulb or envelope 39. The bulb 39 is provided with a reentrant stem 41 through which lead wires 42—43 for electrodes 35 and 36 and lead wires 44—45 for the cathode 37 extend. Extending from the stem 41 and secured thereto by a clamp 47 is a rigid conductive rod 48 25 which connects with a terminal support 49 of the cathode 37. Then another terminal support of the cathode is connected with a conductor 51 connected to lead wire 44.

The rod 48 is provided with a plurality of spacer 30 members 53 which are clamped to the rod and contact with the outer surface of the chamber 38. The members 53 act as a cooling means and cause any condensed vapor to concentrate along the inner surface of the chamber adjacent to these 35 members. If desirable the rod 48 may be made in the form of a T-bar 54, as shown in Fig. 8, to provide a continuous contacting surface 55 along the chamber.

The chamber may be closed at its ends by walls 56 and 57 of any suitable material such as mica. The chamber may be held in a collar 58 and a split collar 59 both of which may be secured to the rod 48.

The device just described may be constructed 45 by first mounting the chamber 38 on the reentrant tube 41 and then sealing the flange of this tube to the end of the bulb 39.

Figs. 6 and 7 show a device in which a sealed envelope 61 is provided with a concentrically disposed chamber 62 of tubular form. In this device electrodes 62 and 63 are disposed at one end of the chamber with conductive support members 65 and 66 within the chamber. One end of the chamber 62 is arranged to slip over a reentrant tube 67. A split ring 68 clamps the end of the chamber and a packing 69 to hold the chamber against endwise movement. The chamber may be closed at one end by a wall 71 which rests on the upper end or press portion 72 of the reentrant stem. The other end of the chamber may be closed by a wall continuous with the side or tubular wall.

It is to be understood that the bulb chambers may be made of any suitable light transmitting 65 material. The chambers within the sealed envelopes serve to restrict the discharge to a path of relatively small area in transverse cross section and by reason of the chambers a heat insulating compartment 73 is provided. This compartment may be evacuated to a high degree and when a metallic vapor such as sodium is used the temperature may be maintained within a range of about 200 to 300 degrees centigrade. It will be understood that the proportions of the

chamber and bulb may be adjusted so that heat dissipation is controlled to maintain the temperature within the desired range.

Whereas heretofore it was necessary to employ a cumbersome and outer vacuum bottle type of heat insulative material the present invention provides a simple construction which is more readily applied to housings such for example as employed for street lighting or in work rooms where it is desirable to avoid the installation of large size units.

Although a preferred embodiment of the invention is shown and described herein it is to be understood that modifications may be made therein without departing from the spirit and scope of the invention as set forth in the appended claims.

What is claimed:

1. A discharge lamp comprising a chamber having a neck portion, means for producing a glow discharge within said chamber, a sealed envelope enclosing said chamber, a reentrant tube in said envelope said tube extending into the neck portion of said chamber for supporting said chamber and a partition separating said tube from said chamber.

2. A discharge lamp comprising a sealed envelope, support wires sealed through a wall of said envelope, electrodes mounted on said support wires, a chamber closed at one end enclosing said electrodes, a tubular portion integral with said envelope and extending interiorly thereof, the other end of said chamber being closed by said tubular portion, and a partition between said tubular portion and said chamber.

3. A discharge lamp comprising a sealed envelope, a tubular stem in said envelope, conductive support wires sealed through said stem, electrodes mounted on said support wires, a chamber enclosing said electrodes, a sleeve integral with said chamber disposed about said stem and a partition separating said sleeve from said chamber.

4. A discharge lamp comprising a sealed envelope, a reentrant tube integral with said envelope, a plurality of electrodes supported from said tube, a bulb enclosing said electrodes, said

bulb having a constricted neck portion fitting said tube.

5. A discharge lamp comprising a sealed envelope, a reentrant tube integral with said envelope, a plurality of electrodes supported from said tube, a bulb enclosing said electrodes, said bulb having a constricted neck portion fitting said tube and means for clamping said neck portion on said tube. 5

6. A discharge lamp comprising a sealed envelope, conductive support wires sealed through a wall of said envelope, a chamber within said envelope, a metallic vapor within said chamber, electrodes mounted on said support wires and disposed at one end of said chamber, a cathode in 15 said chamber at the opposite end thereof, a conductive support member for said cathode extending along the outer side of said chamber and means supported by said support member for confining condensed metallic vapor to a given area. 20

7. A discharge device comprising a sealed envelope, a plurality of electrodes in said envelope, a metallic vapor within said envelope, a member for maintaining a portion of the envelope relatively cool to condense said vapor in a restricted area on the surface of said envelope and a conductive member for one of said electrodes supporting said member. 25

8. A discharge device comprising a sealed envelope, a plurality of electrodes in said envelope, 30 a metallic vapor within said envelope, a member for cooling given portions of the surface of said envelope to cause condensed vapor to be confined to said portions and a conductive member for one of said electrodes disposed adjacent to the 35 outer surface of said envelope supporting said first mentioned member.

9. A discharge device comprising a sealed envelope, a plurality of electrodes in said envelope, a metallic vapor within said envelope a conductive 40 member for one of said electrodes and metallic members carried by said conductive member and disposed in contact with the surface of said envelope to provide a relatively cool area for the 45 deposit of condensed vapor.
